UNITED STATES PATENT OFFICE

2,525,457

LIQUID COOLING MEANS FOR ELECTRICAL APPARATUS

Konstantin K. Paluev, Pittsfield, Mass., assignor to General Electric Company, a corporation of New York

Application February 15, 1944, Serial No. 522,519

1 Claim. (Cl. 174—15)

1

My invention relates to an electrical apparatus and to a circulating system for an electrical induction apparatus.

Heretofore it has been customary to manufacture electrical induction apparatus such as transformers of the enclosed type having a winding with suitable cooling ducts within an enclosing casing which is filled with a dielectric fluid such as oil. In order to provide a cooling arrangement for the oil a heat exchanger arrangement is connected to the casing so that the hot oil which passes through the winding ducts may pass through the heat exchanger and give up the heat which has been received from the winding. Such systems have either depended upon the natural circulation effect due to the difference in temperature between the bottom and top of the transformer casing or an auxiliary pump has been provided for forcing the cooling fluid through the winding ducts and through the heat exchanger and back to the winding ducts again.

It is an object of my invention to provide an electrical induction apparatus of the above mentioned type with an improved arrangement for circulating the cooling and dielectric fluid through the apparatus.

A further object of my invention is to provide a fluid immersed electrical induction apparatus which is thermally efficient in operation.

A still further object of my invention is to provide an electrical apparatus having a loss producing element and a heat exchanger for cooling the dielectric fluid within the apparatus with an improved arrangement for circulating the dielectric fluid through the apparatus.

Further objects and advantages of my invention will become apparent from the following description referring to the accompanying drawing, and the features of novelty which characterize my invention will be pointed out with particularity in the claims annexed to and forming a part of this specification.

In the drawing Fig. 1 is a sectional side elevation of an electrical induction apparatus which is provided with an embodiment of my invention, and Fig. 2 illustrates a modification of the construction illustrated in Fig. 1.

In the design of electrical induction apparatus such as transformers, windings are provided which have a copper cross section dependent upon the electrical characteristics of the apparatus. Also, in order to cool the winding it is conventional to provide ducts between the various coils, and when concentric cylindrical windings are used ducts are usually provided be-

2

tween the cylindrical windings. The higher the normal operating voltage between the coils or concentric windings the wider must the ducts be in order to provide the desirable insulation characteristics between the windings so as to prevent electrical failure.

The design of efficient coolers or heat exchange arrangements to be used with transformers, however, is not dependent upon electrical characteristics but is dependent upon thermal phenomena and considerations of economy, and it has been customary to employ a fairly large number of cooling tubes in series, and each cooler design requires a certain optimum velocity of the circulating fluid in the tubes. Thus, it is known that the amount of heat exchange between a surface and a fluid is proportional to fluid velocity. But the power required for fluid flow increases approximately as the third power of its velocity, so the optimum velocity is dependent upon thermal as well as economical considerations. Thus given an area of cross section through which the cooling oil passes and the optimum velocity to obtain a cooler with the best overall efficiency, a certain quantity of oil will flow into the intake manifold of the cooler and be exhausted from the output of the cooler.

I have determined, however, that the amount of oil flow through the cooler determined by the characteristics mentioned above may be quite different from the optimum quantity of oil flow through the winding ducts, and in conventional transformer constructions since the cooler is connected in a recirculating system so that the oil flows from the casing through the cooler and back to the casing, the oil flow through this series system may be quite different from the optimum quantity of oil flow through either the cooler or winding ducts. This is particularly true in the so called directed flow transformers where baffles are used between the winding and the outside of the casing so that all the oil which is exhausted from the cooler and passes into the transformer casing must pass through the various winding ducts.

In the arrangements illustrated in the drawing I provide ways of circulating the oil or cooling dielectric fluid through the winding ducts and at the optimum quantity and velocity for the design of the winding and through the cooler at the optimum quantity and velocity depending upon the cooler construction, and these two optimum values may be and are usually quite different, particularly in directed flow transformers.

Referring more particularly to Fig. 1 of the

drawing, I have provided an electrical apparatus which includes a core having winding legs 10 and 11 and with windings 12 and 13 surrounding the winding legs. The windings illustrated in the drawing are of the concentric cylindrical type and are provided with ducts for carrying fluid in heat exchange relation with the windings. In the construction illustrated in the drawing it will be seen that two concentric ducts 14 are provided which extend axially through the winding 13 and two concentric ducts 15 which extend axially through the winding 12, but it is to be understood that any suitable number of ducts may be provided. In order to provide what is called directed flow insulating cylinders 16 and 17 are placed around the windings 13 and 12, respectively, and a partition or coil support 18 is placed under the windings and extends to the cylinders. The partition is provided with suitable openings in registry with the ducts. The core and coils are placed in a casing 20 and the cylinders 16 and 17 extend from the bottom 21 of the casing so that the cylinders provide a partition arrangement between the windings and the casing. A suitable dielectric fluid such as oil or gas may be placed in the casing 20.

In order to provide a convenient arrangement for cooling the dielectric fluid a heat exchanger means 23 is provided which is fluidly connected to the casing by pipes 24 and 25. The fluid may be forced through the circulating system by a pump 26 which is operated in any suitable manner such as by an electric motor 27. Thus the fluid may be withdrawn from the casing 20 through the pipes 24 as is indicated by the arrows, pass through the heat exchanger and be discharged into the casing through the pipe 25. The pump 26 may have such characteristics as determined by the cooler 23 so that the oil will pass through the cooler at the optimum velocity and quantity for the particular cooler design. As shown, the pump 26 is of the centrifugal type which is characterized by a relatively high pressure head and a relatively low flow. This is especially suitable for forcing cooling liquid through a cooling radiator as the latter often has a relatively high hydraulic resistance and does not require a large flow of liquid through it in order to obtain optimum cooling.

In order to circulate the dielectric and cooling fluid through the winding ducts at the optimum velocity and quantity determined by the winding design, I provide a second pump means 30 which forces the oil from the area between the partitions 16 and 17 and the casing 20 into the bottom of the ducts and so that the oil will pass through the winding ducts at the optimum velocity and quantity depending upon the area and characteristics of the winding. This circulation is indicated by the dotted line arrows. As shown, pump 30 is of the propeller type which is characterized by a relatively low pressure head and a relatively high flow. This is especially suitable for circulating cooling liquid through winding ducts at the optimum rate for cooling. It will therefore be seen that I have provided a circulatory system including the ducts and two parallel return paths, one return path being between the partition 16 and 17 and the casting 20 and the second return path being through the cooler, or the fluid may be pumped from the pipe 24 through the cooler and to the casing at one rate and through the ducts at another rate. Thus, for example, the flow through the winding ducts may be 4000 gallons per minute while

the flow through the heat exchanger may be 1000 gallons per minute.

In the construction illustrated in Fig. 2 I have shown a modification of the system of Fig. 1 including windings 35 and 36 which have ducts 37 and 38 respectively. The windings are provided in a casing 40 and a heat exchanger 41 is connected to the casing 40 through pipes 42 and 43. In order to force the cooling fluid through the heat exchanger I provide a pump 44, similar to pump 26, which may be operated through an electric motor 45. In order to provide what is called directed flow, a baffle 46 is provided at the bottom of the winding and which extends from the outer surface of the windings to the casing. The baffle, however, is provided with suitable openings which communicate with each one of the ducts. Thus oil below the baffle 46 in order to reach the other side of the baffle must pass through the winding ducts.

In order to provide a convenient arrangement for circulating the fluid dielectric within the casing at its optimum velocity and volume, I provide a second pump 47, similar to pump 30, which operates in an opening 48 in the baffle. The pump 47 may be operated in any suitable manner and in the construction illustrated in Fig. 2 I provide a turbine impeller or bladed wheel arrangement 49 which is rotated by the movement of the fluid due to the pump 44. Thus a directing baffle 50 is provided which communicates with the pipe 43 so that the fluid which is discharged from the pipe 43 is directed against the impeller 49 causing it to rotate. Thus when the pump 44 is operated fluid will be withdrawn from the casing 40 through the pipe 42 as is indicated by the arrows and be discharged into the casing 40 through the pipe 43. At the same time due to the rotation of the second pump 47, oil will pass through the opening 48 as indicated by the dotted line arrows and up through the various winding ducts 37 and 38. Thus the fluid flow in the windings will be the sum of the flows of the pumps. It will be understood that here again by suitably designing the pump the fluid may be forced through the ducts and through the heat exchanger at predetermined rates depending upon the characteristics of the winding and cooler. It will be noted that in the system of Fig. 2 the fluid is exhausted below the baffle so that the fluid flowing through the cooler will flow through the ducts, while in Fig. 1 the fluid is exhausted from the pump through the pipe 25 between the baffle and casing. Thus in the Fig. 2 construction if, for example, the flow through the winding ducts is 4000 gallons per minute and that through the heat exchanger is 1000 gallons per minute, the flow through the opening 48 will be the difference or 3000 gallons per minute.

Although I have shown and described particular embodiments of my invention, I do not desire to be limited to the particular embodiments described, and I intend in the appended claim to cover all modifications which do not depart from the spirit and scope of my invention.

What I claim as new and desire to secure by Letters Patent of the United States, is:

A transformer comprising, in combination, an enclosing tank, a winding assembly therein, a normally vertical duct in said winding assembly, a partition in said tank forming a substantially closed bottom compartment therein having a top opening communicating with the bottom end of said duct, a dielectric cooling liquid substantially filling said tank, a cooling radiator outside

said tank, a centrifugal pump connected to force said liquid through said radiator by withdrawing it near the top of said tank and discharging it into said tank near the bottom thereof and outside of said compartment, and a propeller type pump mounted in another opening in said partition for circulating said liquid through said duct by propelling it from outside said compartment into said compartment.

KONSTANTIN K. PALUEV.
